United States Patent Office

Des. 183,456

Patented Sept. 2, 1958

183,456

CANDY BOX

Blanche R. Henderson, Decatur, and Harry L. Morrill, Jr.,
Marietta, Ga., assignors to Norris, Inc., a corporation of Georgia

Application June 24, 1957, Serial No. 46,699

Term of patent 14 years

(Cl. D58—11)

Fig. 1

Fig. 2

Fig. 1 is a top view of a candy box illustrating my new design.

Fig. 2 is a side elevational view of the candy box shown in Fig. 1.

The sides not shown are the same as the side shown.

The dominant features of my design reside in the portions shown in full lines.

We claim:

The ornamental design for a candy box, as shown and described.
